UNITED STATES PATENT OFFICE.

DAVID F. TABER, OF NEW YORK, N. Y., ASSIGNOR TO DEAN A. BECKWITH,
OF NEW YORK, N. Y.

CARD-INDEX.

SPECIFICATION forming part of Letters Patent No. 727,490, dated May 5, 1903.

Application filed October 23, 1902. Serial No. 128,450. (No model.)

To all whom it may concern:

Be it known that I, DAVID F. TABER, a citizen of the United States, residing at 1456 Bedford avenue, Brooklyn, New York city, in the 5 county of Kings and State of New York, have invented new and useful Improvements in Card-Indexes, of which the following is a specification.

My invention relates to card indexes and 10 catalogues, and has for its object to improve the means for locking or holding in place the cards, to improve the drawer, box, or other receptacle in which the cards are placed, and to provide an improved follower and support 15 therefor.

In the accompanying drawings I have illustrated the preferred embodiment of my invention, referring to which—

Figure 1 is a perspective view, parts being 20 broken away, of a drawer for a card-index to which my improvements have been applied. Fig. 2 is a top plan view, parts being broken away. Fig. 3 is a vertical sectional view taken just inside the front end wall of the 25 drawer and on a plane indicated by the dotted line 3 3 of Fig. 1. Fig. 4 is a detail view showing the locking-rod in elevation and end view and also showing the supporting-disks to which the locking-rod is secured, the latter 30 being shown in elevation. Fig. 5 is a face view of one of the cards.

I have shown my improved means for supporting and locking the cards as applied to 35 and supported in a drawer that is of novel construction. It is formed of sheet metal, having the front *a*, back *a'*, and the sides *b b*. The bottom of the drawer is integral with the sides *b* and is formed with a central depression or channel *c'*, arranged between the two 40 parts *c c* of the floor of the drawer. Along each edge of the bottom is a flange *c''*, formed, preferably, by doubling upon itself the metal of which the drawer sides and bottom are formed. These flanges extend slightly below 45 the channel *c'* and serve as the supports or rests for the drawer.

The cards, one of which is illustrated in Fig. 5, are each formed with a sort of dovetail-shaped notch *d* in its lower edge, and with 50 the notched portions of the cards the locking-

rods *E* engage. Two locking-rods are used, and they are connected together, so as to be simultaneously operated. I prefer that these rods should be formed of metal and that in form they be segments of a cylinder or tube. 55 These rods are arranged to be oscillated about axes situated in the plane of the floor *c* of the drawer, so as to be moved into the depression or channel *c'* when in their inactive position, or to be projected above the plane of the floor 60 and into position to enter the notches *d* of the cards, as indicated by dotted lines in Fig. 3, when in locking position. In order to support the locking-rods, I provide them at their ends with spurs or projections *e*, that are 65 adapted to enter apertures *f* in supporting-disks suitably supported upon axes *g*, about which the locking-rods oscillate. The disks *G*, to which the rear ends of the locking-rods are connected, are preferably plain and are of 70 such size that their peripheries are in engagement, though they may be of smaller size, if preferred. The disks to which the forward ends of the locking-rods are connected are constructed to constitute gearing by which both 75 of the rods are caused to move simultaneously. The form of gearing which I prefer to employ is a pair of intermeshing spur-wheels *G' G''* of equal size, and in order to operate the spur-wheels and locking-rods I employ a master-wheel *H*, arranged to mesh with one of the 80 spur-wheels. I prefer that the wheel *H* should be arranged above the wheels *G' G''* and midway between their axes. As the operating or master wheel *H* engages with but one of the 85 intermeshing wheels—the one lettered *G'*—uniting the locking-rods, it should be arranged in a different vertical plane from the other wheel *G''* in order that the two wheels may be freely operated without interfering 90 one with the other. This result I effect by making the wheel *G'* considerably thicker than either the wheel *G''* or the wheel *H*, as clearly represented in Figs. 1 and 2. By this arrangement I am enabled to make the gear 95 ing for the operating locking-rods very thin, so that in case a wooden drawer be used it may be mounted entirely within a chamber formed in the front piece of the drawer or where the drawer is made of metal, as shown 100

in the drawings, it may be arranged close to the front piece *a* and surrounded by a casting *I*. The wheel *H* is mounted upon a shaft *J*, that extends through the front of the drawer, where it may be provided with an operating-handle *K*. Instead of such a handle the shaft *J* may be shaped to receive a key—such as, for instance, is used for winding clocks—by means of which the wheel is turned. The means for operating the locking-rods which I have described permit the shafts *J* to be arranged in the vertical central planes of the drawers, thus preserving symmetry of appearance.

15 I preferably combine with the means for operating the rods a limiting-stop. As shown in the drawings, this may consist of a pin *O*, arranged to limit the movements of the operating-wheel *H*, stopping it when the locking-rods are in raised position to properly engage with the notches of the cards and also when the rods are retracted and out of working position.

The follower or compressor *L* is supported upon a rod *M*, mounted in the channel portion *c'* of the bottom of the drawer and midway between and below the locking-rods. The follower is attached to a slide *N*, that consists of a block *n*, surrounding and traveling upon the rod *M*, a standard or shank *n'*, extending upward from the block between the locking-rods *E*, and the head *n''*, to which the follower or compressor is secured. I prefer that the compressor should be made of sheet metal and that it should have the front inclined face *l*, against which the cards rest, and the rear vertical member *l'*. The compressor may be strengthened by an inclined brace *l''*, arranged between the parts *l* and *l'*, when this is found desirable. The locking-rods being arranged upon opposite sides of the stem of the support for the follower or compressor operate to prevent undue oscillation or sidewise movement of the follower.

45 Besides the advantages which have been already pointed out, these may be referred to: The rod *M*, upon which the support for the follower or compressor *L* is mounted, is arranged in the same recess or part of the drawer that the locking-rods enter when in their retracted or inactive position, and by constructing the operating mechanism as described I am enabled to separate the locking-rods to any desired extent to permit the passage between them of the support for the follower without interfering with their operation.

Having described my invention, what I claim, and wish to secure by Letters Patent, 60 is—

1. The combination with a pair of oscillating rods arranged to engage with and hold the cards of a card-index, and connecting-gearing for simultaneously operating such locking-rods, of a master or operating wheel mounted upon a shaft located vertically to

one side of and midway between the axes about which the locking-rods oscillate, and engaging with one member of the said connecting-gearing, substantially as set forth. 70

2. The combination with a pair of oscillating rods arranged to engage with and hold the cards of a card-index, a pair of intermeshing gear-wheels connected with the locking-rods and arranged to simultaneously operate them, and a receptacle for holding the cards in which the locking-rods are mounted, of a master or operating wheel engaging with one of the gear-wheels that connect the locking-rods, the said operating-wheel being mounted upon an axis which is vertically to one side of the horizontal plane cutting the axes of the locking-rods, and is midway between them, and a handle for manipulating the operating-wheel extending through the front wall of the receptacle, substantially as set forth. 80

3. The combination with a pair of oscillating rods arranged to engage with and hold the cards of a card-index, and a pair of gear-wheels for simultaneously operating the locking-rods, of an operating or master wheel engaging with one only of the said gear-wheels, and arranged with its axis vertically to one side of the axes of the locking-rods and the gear-wheels which connect them, and midway between them, the operating or master wheel being arranged in a different vertical plane from that in which the gear-wheel with which it does not engage is arranged, substantially as set forth. 90

4. The combination with a pair of oscillating rods arranged to engage with and hold the cards of a card-index, and the intermeshing gear-wheels *G'* *G''* which connect them and cause them to be simultaneously moved, 105 the wheel *G'* being thicker than the wheel *G''*, of a master-wheel *H* arranged to engage with the wheel *G'* and being situated in a different vertical plane from that in which the wheel *G''* is situated, whereby the wheels *G''* and *H* 110 are free to turn without interfering with each other, substantially as set forth.

5. A receptacle for a card-index formed of sheet metal having a central recess *c'* in its bottom adapted to receive the card-locking mechanism, and the flanges *c''* at the bottom edges of the receptacle, substantially as set forth. 115

6. In a card-index, the combination of a pair of card-locking rods, means for oscillating the rods to cause them to engage with or disengage from the cards, a follower or compressor, and a support for the follower extending up between the card-locking rods, substantially as set forth. 120

7. In a card-index, the combination of a receptacle for the cards having a central recess *c'*, a pair of card-locking rods arranged to engage with and hold the cards and to be turned into the recess when in inactive position, means for operating the locking-rods, a follower or compressor, a support for the fol- 130

lower or compressor, and a slide-rod upon which the support is mounted arranged in the recess c' , substantially as set forth.

8. In a card-index, the combination of a pair of card-locking rods, means for operating the rods, a follower or compressor, a support for the follower or compressor extending up between the card-locking rods, and a rod upon which the said support is arranged to slide situated below the card-locking rods, substantially as set forth.

9. In a card-index, a locking-rod of segmental shape having at its ends projecting spurs e , in combination with supporting disks formed with apertures with which such spurs are adapted to engage, substantially as set forth. 15
